CLAIM

(22) Filed: **Aug. 8, 2012**

The ornamental design for a food drawer cover plate with a sealing system, as shown and described.

DESCRIPTION

(63) Continuation of application No. 12/710,772, filed on Feb. 23, 2010.

FIG. 1 is a front top perspective view of the food drawer cover plate with a sealing system showing my new design;
FIG. 2 is a rear perspective view thereof;
FIG. 3 is a left side elevation view thereof;
FIG. 4 is a top view thereof;
FIG. 5 is a bottom view thereof;
FIG. 6 is a front elevation view thereof;
FIG. 7 is a rear elevation view thereof; and,
FIG. 8 is a rear perspective view showing the silicone sealing strip partially lifted.

(51) **LOC (9) Cl. 15-07**

In the drawings, the broken lines show details that form no part of the claim. In addition, the broken lines and the separation lines indicate that the drawer cover plate may have any of a variety of length dimensions.

(52) **U.S. Cl. D15/89**
